(57) **CLAIM**

I claim an ornamental design for a tie tail cut-off shield, as shown and described.

DESCRIPTION

FIG. 1 is a perspective view of an embodiment of the tie tail cut-off shield;

FIG. 2 is a right side elevation view thereof;

FIG. 3 is a left side elevation view thereof;

FIG. 4 is a top plan view thereof;

FIG. 5 is a front elevation view thereof; and,

FIG. 6 is a back elevation view thereof; and the bottom of the tie tail cut-off shield is unornamented.

The tie tail cut-off shield is part of a cable tie that may be used to bundle a plurality of items, such as electrical wires in a wiring harness. The tie tail cut-off shield inhibits contact with a cut off end of a cable tie tail.

The broken lines are for the purpose of illustrating the environment of the article only and form no part of the claimed design. The shading illustrated in the drawings is provided merely to highlight the contour of the design and is not intended to be illustrative of any texture or gloss.
